UNITED STATES PATENT OFFICE.

CHARLES SEYBOLD, OF CINCINNATI, OHIO.

PERFORATING-MACHINE.

SPECIFICATION forming part of Letters Patent No. 396,240, dated January 15, 1889.

Application filed March 4, 1887. Serial No. 229,678. (No model.)

To all whom it may concern:

Be it known that I, CHARLES SEYBOLD, a citizen of the United States, residing at the city of Cincinnati, in the county of Hamilton 5 and State of Ohio, have invented certain new and useful Improvements in Perforating-Machines, of which the following is a specification.

The object of my invention is to produce a 10 machine for perforating paper or similar material in which the feed and punching mechanism can be regulated and in which the feed and punching mechanism are automatic.

In the accompanying drawings, forming 15 part of this specification, Figure 1 is a front view of my machine in elevation. Fig. 2 is an end view of the left-hand side of the machine. Fig. 3 is an end view of the right-hand side of the machine. Fig. 4 is a view of the left- 20 hand end of the machine, looking toward the inside from the right, the feed-rolls, shafts, bridge, &c., being shown in section. Fig. 5 is a cross-section through the punch-bar, punch-bar key, and mechanism for working the 25 punch-bar key in and out of the eccentric-rods to raise or lower the punch-bar carrying the punches. Fig. 6 is a section showing the yoke, friction-disks, angle-lever, segment-cam or wedge-stud, pin, and accompanying mechanism. Fig. 7 is a side view of one of the 30 perforating-punches. Fig. 8 shows the perforating-punch attached to the punch-bar, the lower portion of the punch being in cross-section. Fig. 9 is a bottom view of the perforating-punch. Figs. 10 and 11 are views of 35 the mechanism for raising and lowering the feed-roll and gage. Fig. 12 shows a roller, the levers M', and the gages M³ in position. Figs. 5, 6, 7, 8, and 9 are details drawn to a 40 larger scale than the other figures, and are nearly one-half of the actual size of the machine shown.

The letter A represents the frame of the machine, similar on both sides. A' represents the left-hand end, and A² the right-hand end, of the machine. These ends and the frame A may be made of any suitable contour or shape. The ends A' A² have suitably secured to them, preferably cast in one 45 piece therewith, the pieces A³. These pieces extend outward from the main frame, as shown in Fig. 1, and have two arms, a a, slot-

ted at a' a', to receive the journal-boxes of the feed-rolls. These pieces A³ also contain the central slot or recess, a², in which the boxes 55 of the punch-bar slide. The two arms a a of the pieces A³ are connected by the strip a³. B represents the eccentric or operating shaft, which passes through both ends of the machine and through and supported by the housings B'. On the right-hand end of the machine this shaft B carries the wheel B² and pulleys B³ B⁴, and at the left-hand end the gear-wheel C. To each end of this shaft B is attached an eccentric-connection, C'. To the 60 eccentrics C' are attached at each end of the machine the eccentric-rods D. These rods D pass through the eccentric-yoke D', and are held in position by any suitable means.

The eccentric-rods pass through the heads 70 or caps D², which are hollow and receive the ends of the punch-bar D³. The punch-bar D³ passes through and is supported by the boxes D⁴, which play in the slots or recesses a². The punch-bar D³ in its under side has a groove 75 in which fits and plays the key E. This key is of any suitable construction, and is composed of the long part b and the short part b'.

The parts b and b' of the key E work in and out of the recesses b² in the eccentric-rods D. 80 On a stud, E', rigidly secured at one end to the end of the machine in the housing E², is secured the gear-wheel E³ and the operating friction-disk E⁴. The gear-wheel E³ and operating-disk E⁴ are rigidly secured together 85 by the pins d. Both the gear-wheel E³ and disk E⁴ fit on the stud E' loosely, allowing the disk E⁴ and gear E³ to turn simultaneously when motion is imparted to the gear-wheel E³ by the gear-wheel C. The angle-lever F is 90 loosely fulcrumed on this stud E', and is held in place by the nut d'. This angle-lever F is slotted at d². A block, d³, is attached to the eccentric-rod D. When the eccentric-rod D is in motion, the block d³ slides back and forth in the slot d², and consequently vibrates the lever F. This lever F carries the segment cam or wedge e forward and backward between the block e' on the eccentric-rod D and the cap e². A slot, e³, is cut in the wedge e. Through this slot e³ passes the set-screw e⁴. Between this screw e⁴ and the wedge e is interposed the washer e⁵. By means of this slot e³ and the set-screws e⁴ the wedge e may be set nearer 95 100

to or farther from the cap e^2 and block e' , thus enabling said wedge to enter a greater or less distance between cap e^2 and block e' to suit the feed required.

5 F' represents a stud which passes through the end A' of the machine. It is screw-threaded on its inner end to receive the nut h, by means of which it is rigidly secured in position.

G G' represent two friction-disks held together by the pins h'. (See Fig. 6.) The disk G' has the sleeve h², and the disk G the sleeve h³, the sleeve h² fitting over the sleeve h³, which fits loosely over the stud F'. (See Fig. 6.) The disk G is firmly held in position by the washer h⁴ and nut h⁵. Rigidly attached to the disk G' by screws i is the gear-wheel G². This gear-wheel G² is recessed at i' to receive the spring G³, interposed between the recessed portion of the gear-wheel G² and the washer i² and around the sleeve h² of the disk G'.

H represents a yoke. Through the frame end A' pass the rods i³, having around them the coiled springs i⁴. The yoke H is thrown back into position by these springs, which lie between the yoke-arms j and the frame end A' when the wedge e is on its backward movement. The nut-and-washer connection i⁵ holds the rods i³ in position.

30 The gear-wheel G² meshes with the two gear-wheels H² and H³. (Shown in dotted lines in Fig. 2; also shown in Fig. 1.) These gear-wheels H² and H³ are attached to and operate the lower feed-rolls, H⁴ H⁵. The lower feed-rolls, H⁴ and H⁵, come in contact with and impart motion to the upper feed-rolls, H⁶ and H⁷. These feed-rolls are journaled in boxes k' k² k³ k⁴ on each side, which boxes rest in the slots a' in the pieces A³.

40 The feed-rolls are preferably of the peculiar shape shown in Fig. 1—that is, they have an uneven surface similar to a corrugation—and when not in use, or when it is desired to repair a certain part of the machine, these rollers can be lifted up out of the way and allowed to rest in the arms a.

On the stud J, suitably secured, is the gear-wheel J'. On the same stud, J, is also secured the gear-wheel J². On the eccentric-shaft B 50 is secured the gear J³. The gear J³ meshes with and imparts motion to the gear J², and the gear J' meshes with and imparts motion to the gear J⁴, which turns the shaft K. This shaft is journaled in each side of the machine, passing through the frame side A². On this shaft K is secured the cam K' by the sleeve l.

Loosely secured in each side frame, A' A², of the machine, and extending from one side of the machine to the other, is the rod T. The 60 pawls M and M⁴ are rigidly secured on the rod T, the pawl M on the side where the cam K' is present, and pawl M⁴ on the opposite side. The pawl M has three fingers, t t' t'', shaped as shown in Fig. 10. The pawl M⁴ has only the two fingers t t'', which are similar in shape to the fingers of pawl M. On the feed-roller H⁵ is secured the lever M', having the

slot M², (see Figs. 4 and 10,) in which slot works the gage-block M³. This gage is set to bring the sheet to be perforated properly under the punches. The fingers t of the pawls M and M⁴, while the finger t' of pawl M is passing over the raised surface of the cam K', elevate the feed-roller H⁶, so that the sheet can be properly slid between the rollers to the 75 gage M³, and as soon as this is done the finger t' of the pawl M is riding over the drop portion of the cam, and the roller H⁶ falls into position owing to the fingers t dropping, and the paper is fed under the punches. I pref- 80 erably only employ one gage, M³, but may employ one at each side of the machine. The rod T being loosely secured in the sides of the machine and the pawls rigidly secured to the rod T, allows said pawls to work simultaneously 85 when the finger t' of pawl M is passing over the cam K'. The finger t² of pawl M supports the gage M³, and is thereby adapted to elevate the same at the same time the arm t lowers the roller H⁶. The pin H' carries at its 90 inner end the finger m, secured on the pin by the set-screw m'. On the cam K is secured the block K². Through the slot m³ in this block K² passes the set-screw m³, which secures the block to the cam in one of the holes 95 n. This mechanism on the left-hand end of the machine is the feeding mechanism. I shall now proceed to describe the punching or perforating mechanism.

On the shaft K is the gage-wheel L, carrying 100 the pins n'. These pins n' fit loosely in the holes provided for them and are held in position by the set-screws n², by turning which the pins can be slid back, as shown in Fig. 1.

The sliding box D⁴ on the right-hand side 105 of the machine contains the slot n³ and the recess n⁴. The box D⁴ is held in position by the screws n⁵. In the lower part of the box D⁴ is the screw-threaded hole o, in which is screwed the piece o'. Interposed between 110 this piece o' and the part L' of the piece A³ is the spring L², which supports the punch-bar and box D⁴. Through a hole in the arm L³ and in the piece o' passes a plunger, L⁴. Extending downward from the arm L³ is the 115 rod o². This rod passes through the guide o³, which guide is rigidly attached to the side of the machine, as shown in Fig. 1. Extending from the arm L³ and guide o³ is the spring o⁴. This spring o⁴ pulls the arm L³ and plunger 120 L⁴ downward into position. Attached to the lower end of the rod o² by set-screw p is the double-inclined cam p'. The pins n' ride over these inclined faces on the cam p', and consequently raise or lower the cam, and with 125 it the rod o², and through it the arm L³, which elevates or depresses the plunger L⁴. This plunger L⁴ has the cone-shaped head s and the annular concaved head s', working in the recess n⁴. The ends of the short and long portions of the key E meet in this recess n⁴ and terminate in inclined projections s², which fit 130 and work in the concave portion of the head s'. When the cam p' is riding over one of

the pins n' , the plunger is elevated, and the concave head s' draws the inclined faces of the projections s^2 over its concave face and brings the long and short parts b and b' of the key E together and out of the recess b^2 in the eccentric-rods D , elevating the punch-bar and bringing the punches up off the paper to be perforated; but when the cam p' has passed over one of the pins n' and drops down the cone-shaped head s comes down and parts the long and short portions b and b' of the key E and forces them into the recesses b^2 in the eccentric-rods, and the punch-bar is brought down and the punches into contact with the paper, when they perforate it. When the cam p' rides over another pin, n' , the key is again withdrawn and the punch-bar and punches elevated. By pushing the pins backward, so that the cam p' passes them, the punching is longer continued and the length of the lines of perforations regulated. I provide a pin on the face of the disk or wheel L to correspond with each downward descent of the eccentric-rods or with each rotation of the shaft B —that is to say, every time the eccentric-rods are about to descend one of the pins will come under the cam p' and will operate to raise said cam (and the punch-bar will not be drawn down)—that is, when the pin is in its forward or operative position; but the cam will not be operated, and consequently the punch-bar will be drawn down by the parts b engaging the eccentric-rods when the pin in the wheel L is in its backward or inoperative position.

N represents one of the punches. These punches have two jaws, N' N^2 , which encircle the punch-bar D^3 , and are tightly held in position on the punch-bar by the bolt-connection N^3 . Between the wings w of the punch N lies the block N^4 , which carries the perforating-pins w' . These pins are properly set in this block N^4 , and the metal, N^5 , poured in and around them, by which these pins w' are rigidly held in position.

P represents a stripper. This stripper is held in position by the set-screws w^2 , working in the slots w^3 . I also provide springs w^4 . (Shown in dotted lines in Fig. 7.) When the punch N comes down, the stripper P rests on the paper and holds it tight while the perforating-pins perforate the paper, and as soon as the punch leaves the paper the stripper is again held in position by the springs w^4 . The object of this is to keep the paper from tearing and prevent the paper following the perforating-pins w' . As many of the punches N may be used as desired.

The machine operates as follows: The belt being adjusted on the pulley B^3 , motion is imparted to the eccentric-shaft B , (the paper to be perforated having been adjusted on the bridge R by the gage M^3 and the pins n' , and the block K^2 having been adjusted,) which works the eccentric-rods D and the gear C , meshing and imparting motion to the gear E^3 , which imparts motion to the friction-disk E^4 ,

which, being gripped by the disks G and G' , imparts motion to them, and the disk G' imparts motion to the gear-wheel G^2 , and this gear-wheel meshes with and imparts motion to the gear-wheels H^2 and H^3 , and they operate the lower feed-rollers, they in turn imparting motion to the upper feed-rollers. The eccentric-rod D on the left-hand side of the machine, imparting motion to the block d^3 , which works in the slot d^2 of the lever F , and working back and forth in said slot, tilts the said lever F back and forth, forcing the segment cam or wedge e between the block e' on the eccentric-rod and the cap e^2 , forcing the yoke H inward, and the arms j of the yoke, impinging against the disk G' , press said disk G' away from the operating-disk E^3 , consequently stopping the feed, and in this interval the punch-bar carrying the punches N is depressed and the desired perforations made. The springs i^4 throw the yoke H back into position, and the spring G^3 returns the gear-wheel G^2 and disks G and G' . Gear-wheel J^4 meshes with and imparts motion to the gear-wheel J^4 , which imparts motion to the shaft K , carrying the gage-wheel L , on which are the pins n' , and the wheel L revolving, the pins coming in contact with the inclined faces of the cam p' , the said cam rides over them, thus elevating the rod o^2 , and through this rod the plunger L^4 , and the concave surface of the concave head s' , riding over the inclined projections s^2 on the key E , retracts them from the eccentric-rods D ; but as soon as the cam p' has passed over one of the pins n' it drops and the plunger L^4 falls, the cone-shaped head s forcing the two portions b and b' of the key E apart and into the recesses in the eccentric-rods, and they, being in motion, carry down the punch-bar D^3 with the punches, and the desired perforation is made. This operation is continued until the sheet has passed through the feed-rolls.

While the feed is operating, the pawl M is traveling over the face of the cam K' , and when the finger t' is traveling the raised surface of the cam the finger t raises the roller H^6 , so that the paper can be placed in between the feed-rollers, at the same time allowing the lever M' , with the gage M^3 , to fall, and when traveling the drop-surface of the cam allowing the roller H^6 to fall and raise the lever M' , with the gage M^3 . (See Figs. 4, 10, and 11.)

In order to regulate the feed, the wedge e may be set forward or slightly backward through the agency of the slot e^3 and set-screw e^4 . This will shorten or lengthen the stroke of the wedge.

Suppose the machine is set to punch or perforate every two inches. This requires a feed of two inches at regular intervals; and, again, suppose it is required to punch at two and one-half inches. This makes a fraction of an inch—viz., the half-inch. In order to meet this I adjust the block K^2 in the proper hole in the cam K' , and the finger m on the pin H'

will ride over this block K² and pull the yoke H against the disk G' and allow the feed-rolls to feed one half-inch before the wedge e impinges against the cap e². The regular feed 5 of two inches follows, thus making the required feed of two and one-half inches.

The bridge R is a cast-iron piece extending from one end of the machine to the other. The arrows on the gear-wheels and cams show 10 the direction in which they travel.

What I claim as new and of my invention, and desire to secure by Letters Patent, is—

1. In a perforating-machine, the combination of the shaft B, eccentric-rods, punch-bar 15 D³, provided with a key which engages with said eccentric-rods, cam p', and wheel L, and connecting and operating parts, substantially as set forth.

2. In a perforating-machine, the shaft B, 20 eccentricities, eccentric-rods having notches b², and punch-bar D³, having the key E, in combination with mechanism, substantially as set forth, for causing parts b and b' of said key E to engage and disengage with the notches 25 in the eccentric-rods, substantially as set forth.

3. In a perforating-machine, the combination of the bar D³, carrying key E, rods D, having notches b², box D⁴ being recessed, plunger L⁴, having the concave and convex heads S and S', and mechanism for automatically raising and lowering said plunger at determinate periods, substantially as set forth.

4. In a perforating-machine, the yoke H, 35 rods r³, disks G and G', gears G² and E³, pins h' and d, springs r⁴ and G³, and block e', in combination with wedge or segment e and suitable mechanism for operating said segment backward and forward, substantially as 40 set forth.

5. In a perforating-machine, the combination of shaft B, eccentric-rods having notches b², punch-bar D³, provided with key E, com-

posed of parts b and b', box D⁴, plunger L⁴, provided with means for moving the parts of 45 key E into and out of said notches, arm L³, rod o², spring o⁴, cam p', and wheel L, with pins n', substantially as set forth.

6. In a perforating-machine, the combination of yoke H, disks G, G', and E⁴, and mechanism, substantially as set forth, for operating said disks, substantially as set forth.

7. In a perforating-machine, the cam K', pawl M, having fingers t t' t², rod T, pawl M⁴, lever M', and gage M³, in combination with 55 feed-rolls, substantially as set forth.

8. In a perforating-machine, the cam K' and block K², in combination with finger m, pin H', yoke H, disks G, G', and E⁴, and means for operating said yoke and disks, substantially as set forth.

9. In a perforating-machine, the combination of the shaft B, eccentric-rods, punch-bar D³, provided with a key which engages with said eccentric-rods, and means, substantially 65 as set forth, for enabling said key to engage and disengage with said eccentric-rods, and wheel L, and connecting and operating parts, substantially as set forth.

10. In a perforating-machine, the combination of shaft B, gear-wheels C and E³, friction-disks E⁴, G, and G', gear G², gears H² and H³, attached to rollers H⁴ and H⁵, and rollers H⁴, H⁵, H⁶, and H⁷, substantially as set forth.

11. In a perforating-machine, the mechanism shown and described for automatically stopping the feed while the perforating is being accomplished, and consisting of the rod D, block d³, lever F, having slot d² and wedge or segment e, and suitable mechanism for operating said rod D, substantially as set forth.

CHARLES SEYBOLD.
